UNITED STATES PATENT OFFICE.

EDWARD R. SARGENT, OF NEW HAVEN, CONNECTICUT, ASSIGNOR TO SARGENT AND COMPANY, OF NEW HAVEN, CONNECTICUT, A CORPORATION OF CONNECTICUT.

DESIGN FOR CASKET-TRIMMING.

SPECIFICATION forming part of Design No. 36,959, dated June 7, 1904.

Application filed April 22, 1903. Serial No. 153,874. Term of patent 14 years.

To all whom it may concern:

Be it known that I, EDWARD R. SARGENT, of the city and county of New Haven, State of Connecticut, have invented a new, original, and ornamental Design for a Casket-Trimming, of which the following is a specification, reference being had to the accompanying drawings, in which—

Figure 1 represents a front view, and Fig. 2 an edge view, of a casket-trimming, showing my new design.

What I claim as new, and desire to secure by Letters Patent, is—

The ornamental design for a casket-trimming, as herein shown.

EDWARD R. SARGENT.
